TOY HAND GRENADE

Carl Arnold, Nuremberg, Germany

Application July 6, 1937, Serial No. 152,253
In Germany May 7, 1937

1 Claim. (Cl. 46—196)

Toy-grenades have become known which are brought to explosion by striking perpendicularly upon the ground, be it in consequence of shooting or throwing. In such grenades the point of gravity is placed as far as possible towards the front end, in order to avoid slipping.

The invention relates to a miniature hand grenade which has to be thrown to come to explosion. This grenade must be of very light weight in order to attain the farthest possible throw. When throwing the grenade, it happens almost always that the grenade does not strike on the ground with the head so that the striking bolt mechanism is not released and no explosion takes place. In order to avoid this inconvenience and to securely attain an explosion at every throwing of a hand grenade, the throwing pin projecting from the grenade has an extension on which a disc is fixed which is of slightly larger diameter than the grenade. As this disc acts upon the releasing mechanism the grenade will always explode in whatever position it strikes the ground.

An embodiment of the invention is illustrated by way of example in the accompanying drawing, in which

Fig. 1 shows the inoperative hand-grenade in longitudinal section.

Fig. 2 is a top plan view of Fig. 1.

Fig. 3 is a longitudinal section through the charged grenade.

The grenade consists, in known manner, of a casing *a*, a firing pin *b*, a handle pin *c* and a spiral spring *d*. According to the invention the handle pin *c* is extended and carries a disc *f*, the diameter of which is slightly larger than that of the casing *a*. The handle-pin *c* has further a lateral projection *g*, which when the handle pin is pulled back, engages in an indentation or behind a projection *h* of the grenade plate *i* and maintains the firing pin *b* under tension. The primer is introduced into the casing *a* through an aperture *l* in this casing.

I claim:—

A toy grenade, comprising in combination with a casing, a head plate on said casing, and a spring controlled firing pin in the lower end of said casing, a handle pin fixed in said firing pin and projecting from the head plate of said casing, a disc on said handle pin outside the cover plate of said casing said disc being of larger diameter than said casing, a projection in said casing and a lateral projection on said handle pin adapted to engage behind said projection in the casing, when said handle pin is pulled back for throwing the hand grenade.

CARL ARNOLD.
